ROTARY DRYER

George P. Forni, Emeryville, Calif.

Application June 17, 1944, Serial No. 540,810

3 Claims. (Cl. 34—137)

1

The present invention relates to improvements in a rotary dryer, and it consists of the combinations, constructions and arrangements herein-after described and claimed.

An object of my invention is to provide a rotary dryer in which the space surrounding the material to be dried is reduced in proportion to the shrinkage of the material during the drying process so that the heated air will be kept in intimate contact with the material at all times. I have found that where the drying space was of the same size throughout, there is a tendency for the hot air to pass over the material when the material has shrunk to a point where it will occupy little space. By reducing the space through which the material passes in direct ratio to the shrinkage of the material, I cause the dryer to operate more efficiently.

I provide a tubular dryer that rotates about a longitudinal axis that is inclined at an angle sufficient to cause the material to advance along the dryer during the drying operation. The tubular dryer has sections that are progressively reduced in diameter. I make use of novel means for advancing the material from a larger tubular section into a smaller one, this same means tumbling the material as it moves through the dryer in order that all parts may be subjected to heat for drying purposes. The device is simple in construction and the drying tube itself with the material lifting means consists of but one rotating part.

Other objects and advantages will appear in the following specification, and the novel features of the device will be particularly pointed out in the appended claims.

My invention is illustrated in the accompanying drawings forming a part of this application, in which:

Figure 1 is a longitudinal section through the entire device;

Figure 2 is a transverse section taken along the line 2—2 of Figure 1;

Figure 3 is a transverse section taken along the line 3—3 of Figure 1;

Figure 4 is a transverse section taken along the line 4—4 of Figure 1;

Figure 5 is an isometric view showing a diagram of the rotating tube; and

Figure 6 is a transverse section taken along the line 6—6 of Figure 1.

While I have shown only the preferred forms of my invention, it should be understood that various changes or modifications may be made within the scope of the appended claims with-

2

out departing from the spirit and scope of the invention.

In carrying out my invention I provide an elongated tube or cylinder indicated generally at 5. This tube may be of any length desired and I find that in the drying of garbage it should be about one hundred feet long. The tube has outer supporting rings 1 and 2 mounted thereon and the diameters of the rings are equal. Figure 4 shows the ring 1 supported by idle roller sets 3 which in turn, are pivotally mounted at 4 on a plate 5. The plate is supported by a concrete base 6. The ring 2 is carried by roller sets 7 which are of the same construction as the roller sets 3 and the roller sets 7 are supported on a concrete base 8. The axis of the drying tube, indicated by the dot dash line 9 is inclined so that the entrance end 10 of the tube is disposed at a sufficient height above the exit end 11 so that the material will move along the cylinder as the latter is rotated. The angle of inclination can be altered to suit the particular requirements.

The entrance diameter of the tube is preferably six feet. The section A1 of the tube has the same entrance diameter, while the central section A2 has a four and one-half foot diameter. The end section A3 has a three foot diameter. I do not wish to be confined to any particular measurements because the diameters of the tube sections and the number and lengths of the sections may be changed in accordance with the requirements. The entire interior of the tube is preferably lined with a layer of fire-brick 12. The tube is rotated at approximately five revolutions per minute by the mechanism shown in Figure 1. A ring gear 13 is mounted on the central section A2 and meshes with a pinion 14 which in turn, is rotated by a gear reducing mechanism indicated generally at 15 and operatively connected to an electric motor 16. Any type of tube rotating mechanism will suffice.

The tube is prevented from moving longitudinally in the direction of its lower end by a thrust wheel 17 that bears against the face of the ring 45 1 adjacent to the rim and is rotatably carried by the plate 5 and concrete base 6. If desired, additional thrust wheels may be used.

The entrance end 10 of the tube projects into a chimney 18 that has a smoke-stack 19 communicating therewith. A valve or damper 20 controls the flow of hot gases through the smoke-stack. A protecting flange 21 is mounted on the tube or cylinder adjacent to the entrance end and is rotatably received in an annular groove 55 22 for the purpose of preventing any heated

gases from escaping into the atmosphere before they pass into the smoke-stack.

Any means for feeding the material to be dried may be used and I have shown an oscillating hopper 23 in Figures 1 and 2. The hopper 23 is 5 in the form of a half cylinder with a closed end 24 and an open end 25 that delivers the material, such as garbage, into the entrance end of the tube. Pairs of legs 26 and 27 are pivoted to the hopper and to a base plate 28 which in turn is 10 mounted on a concrete base 29.

Means for reciprocating the hopper comprises a cam 30 rotated by a motor 31 and a gear reducing mechanism 32. The cam 30 contacts with a cam follower 33 which is attached to the 15 hopper. A stop 34, preferably of rubber, is disposed in the path of the cam follower 33 and prevents it from contacting with the cam when the lowest point of the cam is reached. The cam 30 moves the hopper to the right while coil springs 35 move the hopper to the left. The material is placed in the hopper and is fed into the entrance end of the tube in a uniform stream due to the reciprocation of the hopper.

The novel means for lifting the material as it moves from one section of the tube to a smaller section, comprises a series of steps or cup-shaped portions B1 and B2. Figure 5 shows the step or pocket B1 as having a width equal to a half circumference of the tube and as having a radius equal to the radius of the entrance end of the tube. The step B1 extends into the central section an appreciable distance and has inwardly extending shoulders 36 that are disposed opposite to each other. When the step B1 is at the lowermost portion of the tube during the rotation of the latter, the material in the section A1 will gravitate into the step B1 which in reality is an extended portion of the section A1. The material received in the extended section B1 will tend to remain at the bottom of the section, even while the latter is rotated. The material will move along the wall during the rotation until it comes to the shoulder 36. At this point the shoulder will engage with the material and as the shoulder is carried upwardly by the tube, it will tumble the material onto the section A2. Continued rotation of the tube will eventually cause all of the material in the section A1 to be lifted by the rotating shoulders or vanes 36 into the central section A2.

The same process is repeated when moving the material from the section A2 into the end section A3. Here the step B2 receives the material from the section A2 when the former is at the bottom of the tube. The extended section or cup-shaped portion B2 has the same radius as the central section and the shoulders 37 will lift the material into the end section A3. The portion B1 is disposed 180° from the portion or pocket B2.

The material as it is dried will shrink and the purpose of the gradually reducing diameters of the sections is to compensate for this shrinkage. If the exit end of the tube were the same diameter as the entrance end, the flame issuing from the burner 38 and the hot air produced by the flame, would flow along the upper portion of the tube and not be brought into intimate contact with the material for drying it. By reducing the diameter of the tube a number of times through a number of sections, the drier material even though occupying less space will be brought into contact with the heated air because this material is moving through a tube section that has a much smaller diameter. The 75

novel feature of the invention is to move the material into tube sections of progressively decreasing diameters by a mechanism that has no moving parts and is in reality a permanent part of the tube itself.

At the exit end of the tube A, I show a housing 39 that has an endless conveyor 40 for carrying away the ash and any unburnable material, such as tin cans and the like. A door 41 gives access to the housing and to the conveyor. A sealing flange 42 mounted on the tube and rotatable in a groove 43 in the housing prevents the flame and the hot air from escaping and causes the flame and the hot air to pass into the tube.

From the foregoing description of the various parts of the device, the operation thereof may be readily understood. I have explained the greater part of the operation of the invention during the description of the structure. The tube may be rotated at any desired speed and the vanes or lifters 36 and 37 may be of any desired shape and size. The steps or cup-shaped portions B1 and B2 receive the material even though it is very fine because the material tends to move along the bottom of the tube. The vanes raise the material and drop it so that it passes through the path taken by the heat. The steps prevent the material from slipping along the bottom of the tube from the entrance to the exit end without being lifted. The steps may be likened as extensions of the tube sections from which they extend and they permit the material to move from the larger sections into the entrance ends of the smaller sections without piling up on any annular shoulders.

In certain cases the material, when dried, might expand rather than shrink and in these cases the tube would be reversed so that the entrance end would be the small one and the exit end, the large one. The burner 38 creates a temperature of about 1500° Fahrenheit, which is sufficient to burn the dried garbage as it passes through the end section A3. The garbage may be delivered into the tube at the entrance end in a wet condition. The garbage will be thoroughly dried before it reaches the small end A3 and then the dried garbage will be burned. In fact, the burning garbage at the exit end will furnish additional heat for drying the garbage entering the device and in certain cases it is possible to shut down the burner 38 by closing a valve 44 after the device has been set in operation because the burning of the dry garbage dries the wet garbage to a point where it can be burned.

I claim:

1. In a rotary dryer, a rotatable tube inclined downwardly from the inlet to the outlet end, means for rotating the tube for causing material received at the inlet end to gravitate toward the outlet end of the tube, means for directing heated air through the tube, said tube being divided into a plurality of interconnected sections of progressively reduced diameters from the inlet to the outlet end, the axes of all of the sections being aligned with the axis of rotation of the tube, each section except the outlet end section having semi-cylindrical portions of the same radius as its respective section extending an appreciable distance into the next smaller diameter section, the said next smaller diameter section having a cut out portion communicating with the semi-cylindrical portion of the next larger section, the overlapping of the semi-cylindrical portion into

the next smaller section forming a pocket with a semi-circular step at its juncture with the smaller section and two longitudinally extending and diametrically opposed shoulders that extend throughout the length of the pocket, each pocket causing its longitudinal shoulder to lift the material thereon and empty it into the next section when the rotation of the tube is in a position to dispose the pocket in the upper tube half, the material in dropping from the shoulder by 10 gravity, passing through the tube interior and thus being heated.

2. In a rotary dryer, a rotatable tube inclined downwardly from the inlet to the outlet end, means for rotating the tube for causing material received at the inlet end to gravitate toward the outlet end, means for directing heated air through the tube, the tube being divided into a plurality of interconnected sections of progressively reduced diameters from the inlet to the outlet end, each section except the outlet one having semi-cylindrical portions of the same radius as its respective section extending an appreciable distance into the next smaller diameter section, the said next smaller section having a cut out portion communicating with the semi-cylindrical portion of the next larger section, the overlapping of the semi-cylindrical portion into the next smaller section forming a pocket with a semi-circular step at its juncture with the smaller section and two longitudinally extending shoulders that extend throughout the length of the pocket, each pocket causing its longitudinal shoulder to lift the material thereon and empty it into the next section when the rotation of the tube changes the angle of the shoulder for dropping its material into the next smaller section, the material passing through the heated air during its drop from the shoulder.

3. In a rotary dryer, a rotatable tube inclined downwardly from the inlet to the outlet end, means for rotating the tube for causing material

received at the inlet end to gravitate toward the outlet end, means for directing heated air through the tube, the tube being divided into a plurality of interconnected sections of progressively reduced diameters from the inlet to the outlet end, each section except the outlet one having semi-cylindrical portions of the same radius as its respective section extending an appreciable distance into the next smaller diameter section, the said next smaller section having a cut out portion communicating with the semi-cylindrical portion of the next larger section, the overlapping of the semi-cylindrical portion into the next smaller section forming a pocket with a semi-circular step at its juncture with the smaller section and two longitudinally extending shoulders that extend throughout the length of the pocket, each pocket causing its longitudinal shoulder to lift the material thereon and empty it into the next section when the rotation of the tube changes the angle of the shoulder for dropping its material into the next smaller section, the material passing through the heated air during its drop from the shoulder, the adjacent pockets in the tube being angularly disposed with respect to each other.
